STEPHEN L. YOUNG, OF SYRACUSE, NEW YORK.

SIGNAL.

1,083,978.

Specification of Letters Patent. Patented Jan. 13, 1914.

Application filed June 10, 1912. Serial No. 702,926.

To all whom it may concern:

Be it known that I, STEPHEN L. YOUNG, a citizen of the United States, residing at Syracuse, in the county of Onondaga and State of New York, have invented certain new and useful Improvements in Signals, of which the following is a specification.

This invention relates to improvements in signals such as are used with fire pails and other liquid receptacles for indicating automatically when the liquid has fallen below a predetermined level; and it comprises a visual indicator on the outside of the liquid receptacle together with a float or other means within the receptacle, operable by the liquid for holding such indicator normally in elevated position and releasing the same when the liquid has fallen and the receptacle needs filling; and more specifically it comprises such a visual indicator and float provided with spring clamps for holding the indicator and float detachably to the edge of the fire pail or other receptacle; and it also comprises certain novel features of construction and arrangement of parts; all as more fully hereinafter set forth and as claimed.

In liquid receptacles such as fire buckets, which are required to be maintained in large number in mills, on ships, and in factories, continual evaporation of the liquid takes place, with the result that frequent inspection is necessary to insure that the required amount of water still remains in the bucket, and to fill those buckets in which the level of the liquid has been lowered too much by evaporation, leakage or otherwise. Frequently such fire buckets are placed on shelves where they are out of the way and where the level of the liquid cannot be seen. As a result it is necessary either to spend an excessive amount of time in inspecting such buckets individually or to provide some means for indicating when the water in the buckets needs replenishing. In automatic devices as heretofore made an elaborate and complicated mechanism has been used, or mechanism which interferes with the utilization of the bucket when necessary. Clock-work mechanisms have also been proposed but these mechanisms are also elaborate and expensive. Moreover such mechanisms which depend on the ringing of a bell or other sound indicators become inoperative if nobody is present to hear them.

It is the object of the present invention to

provide an automatic signal device which is simple and reliable in operation; which will operate to indicate the lowering of the liquid level below a predetermined point and remain in operative position until manually replaced; which will not interfere with the use of the bucket in case of fire, but which can be readily removed when desired; and which is inexpensive to manufacture and not liable to get out of order or to become inoperative.

In the accompanying drawings illustrating the invention, and showing certain specific embodiments of it, Figure 1 is a perspective view of a fire bucket with the visual indicator in lowered position. Fig. 2 is another view showing the visual indicator elevated and the bucket full of water, part of the float casing being broken away. Fig. 3 shows a modification of the signal attachment. Fig. 4 shows still another modification in section on the line 4-4, Fig. 5. Fig. 5 shows a section on the line 5-5, Fig. 4, and Fig. 6 shows still another modification of the invention.

In the embodiment of the invention of Figs. 1 and 2 a fire bucket 1 is shown on a suitable support, and with the signal device of the present invention attached. This device is made up of the gravity operated signal or indicator 3 pivotally supported by the wire supports 4 on the outside of the bucket in unstable equilibrium and on the inside of the bucket is a float casing 5 also supported by the same wire support indicated at 6, which extends into recesses 7 formed in the periphery of the float casing. These wires are fastened to the float casing by soldering, brazing or otherwise. Inside the float casing 5 is a float 8, shown as made of cork and provided with a guide wire 9 extending through the top and bottom of the float casing, for the purpose more fully hereinafter explained. The float casing 5 is provided with a top 10, preferably made of copper or other metal not corroded by water, and this top 10 is provided with a vent hole 11. The bottom of the casing is similarly constructed with an opening 12. The wire support 4, 6, 105 is shown as made of a single piece of wire with its ends attached to the float casing and held together by soldering at 16. This wire is formed as a spring clamp of inverted U-shape which can be readily attached to, or detached from, a pail or bucket, and which when attached is held in place on the side of

the bucket by its spring action. This wire is bent to form an additional guide loop 13 for the float guide wire, and also to form upright loops 14 which serve as guides for the extension member 15 of the signal 3 both when raised, and when released, and thus insure alinement of the hole 20 and rod 9; and also insure that the signal when released, falls directly downward. These loops 14 also furnish convenient holds for removing the device hurriedly in case of fire. The gravity actuated signal 3 on the outside of the bucket is shown in Fig. 1 in its lowered position, and in Fig. 2 as raised and supported in unstable equilibrium. This signal is shown as provided with depressions 18 for the wires 4 and also with a depression 19 for the bead 2 on the top of the bucket. Extending upwardly and inwardly from the signal 3, and shown as integral with it, is the catch or tongue 15 provided with a relatively large hole 20 for the float guide wire.

In operation, if the pail is empty and the signal is down, as shown in Fig. 1, the float is also in a lowered position in its casing, as shown. When the pail is filled with water, as in Fig. 2, the float is raised as indicated, the arrangement and size of the float being such as to insure the desired operation. When, now, the signal 3 is raised the tongue or catch 15 will be guided by the wires 14 and will, owing to its extending both upwardly and inwardly, engage the upper end of the float rod 17 and depress it until this rod is held by the hole 20 into which it extends, (see Fig. 3). Thus it is not necessary to manually depress the float rod, but merely to swing the signal into its elevated position when it automatically catches. When now the water level falls, owing to evaporation, leakage or otherwise, the float also falls and as it falls sufficiently to withdraw the end of the rod 17 from the hole 20 the signal will be released and will fall to the position shown in Fig. 1, thus indicating at a glance that the bucket needs refilling. This signal conforms to the shape of the bucket when elevated and is made on its outside of the same kind of material as the bucket, *e. g.* galvanized iron; but on its inside it is painted an attractive red to draw attention. The float casing protects the float from the direct impact of the water in the bucket and thus prevents releasing the signal when the bucket is given a sudden jar, or the water is otherwise agitated, but the holes 11 and 12 allow gradual inflow and outflow of water and air so that the liquid level within and without the casing readily becomes and remains the same. As already indicated, the top and bottom of the float casing which are subjected to the wearing action of the float rod, are advantageously made of copper, and the guide wire of brass. The wire supports

4, 6 are also preferably made of rather stiff copper or brass wire.

Fig. 3 shows a modification of the signal attachment in which the guide rod 9 is guided by guide loops 22 and 23 formed in the same wire that supports the signal from the side of the bucket. In this structure the float casing is omitted and the entire signal constructed of the gravity signal member, the wire support, and the float and float rod. Inasmuch as most fire buckets are smaller at the bottom than at the top, the outside of the buckets tapers inwardly from the top down, so that the hinge of the gravity operated signal is inside the center of gravity of the signal. As a result the signal is supported in unstable equilibrium and when it is released at its upper end it falls freely and readily by gravity to its lowered position. This relative location of the hinge is shown in Fig. 4. Additional means may be provided, however, supplemental to, or in lieu of, such a gravity arrangement. Fig. 3 shows such a supplemental spring in the form of a bend in the supporting wire 4 at 21. When the catch 15 is released this spring assists in starting the signal downward, after which it continues to fall by gravity.

In Figs. 4 and 5 a hollow instead of a cork float is shown at 24 provided with detachable guide rods 25 and 26; and in this modification the guides are shown as plates, preferably of copper, 27 and 28, permanently attached to the side of the bucket, as by rivets or otherwise. The signal 3 in this figure is supported by the spring wires 30 which extend over the edge of the bucket and pass through holes in the guide plates. The signal is thus readily detachable but accurately positioned with respect to the float when in operative position.

In Fig. 6 a modification is shown similar to that of Figs. 1 and 2 but with the signal and float casing independently detachable from the bucket. The outer wire 4 has spring projections 32 extending inside the bucket and the inner supporting wire 6 has projections 31 extending outside the bucket. For insuring the correct relative positioning of the signal and float the wires 31 are both outside the corresponding wires 32.

Since the device of the present invention is attached only to the side of the bucket it does not interfere with its use in case of fire; but at the same time, in the modifications shown, a part or all of the device is easily and quickly detachable when desired.

While the device has been shown as applied to fire buckets, it is also adapted for use with reservoirs, tubs, and tanks of various descriptions in a similar manner.

I claim.

1. A signal device for fire buckets comprising in combination a spring support made

up of wire, provided with a spring loop for attaching to the side of a receptacle and extending downwardly on both sides thereof, a signal device supported pivotally at one of the lower ends of said spring support, a float, a guide rod for said float and a guideway for said rod formed in the other end of said spring support, said signal device being arranged to be operated by the falling 10 of said float rod, substantially as described.

2. A signal device comprising in combination a liquid receptacle, a gravity actuated visual indicator supported in unstable equilibrium on the outside of said receptacle and 15 extending inside the top thereof, a float adapted to be operated by the liquid in said receptacle, and means carried by said float for normally holding said indicator and for releasing the same when the liquid in said 20 receptacle falls below a predetermined level.

3. A signal device comprising spring attaching means adapted to be secured to the side of a liquid receptacle, a visual indicator supported in unstable equilibrium at its 25 lower end by said spring attaching means, and float actuated means for normally restraining and for releasing said visual indicator.

4. A signal device comprising in combination a liquid receptacle, a visual indicator supported at its lower end on the outside of said receptacle and normally held in unstable equilibrium, a float inside said receptacle, and means carried by the float for normally restraining and for releasing said 35 indicator.

5. A signal device comprising in combination with a liquid receptacle spring attaching means adapted to be secured to the side 40 of said liquid receptacle, a visual indicator on the outside of said receptacle, a float in said receptacle, a guide for said float formed by an extension of said spring attaching means, and means actuated by the float for 45 normally restraining and for releasing said indicator.

6. A signal device comprising spring attaching means adapted to be secured to the side

of a liquid receptacle, and to extend downwardly from the top of said receptacle both 50 interiorly and exteriorly thereof, a visual indicator supported at its end by the exteriorly downwardly extending portion of said attaching means, a float provided with a float rod, and guides for said float rod carried by the interior extending portion of 55 said attaching means, said float rod being arranged to engage the unsupported end of said indicator when in adjusted position.

7. A signal device comprising in combination a liquid receptacle, a visual gravity operable indicator supported in unstable equilibrium on the outside of said receptacle below the top thereof and provided with an extension projecting inside the edge of said 65 receptacle, a float in said receptacle, and a rod carried by the float for engaging said extension and releasing the same upon the falling of the float.

8. A signal device comprising in combination a liquid receptacle, a visual gravity operable indicator supported at its lower end in unstable equilibrium on the outside of said receptacle below the top thereof and provided with an extension projecting inside the edge of said receptacle, a float in 70 said receptacle, a guide for said float, and a guide rod carried by said float for engaging said extension and releasing the same upon the falling of the float.

9. A signal device comprising in combination a liquid receptacle, a signal on the outside of said receptacle and provided with an extension extending inside the top thereof, a float in said receptacle responsive to liquid 85 level therein, and means carried by said float arranged to engage and normally restrain the extension of said signal, and to release the same upon lowering of the liquid level.

In testimony whereof, I affix my signature in the presence of witnesses.
